UNITED STATES PATENT OFFICE.

EVERETT W. VARNEY, OF NEWTON, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

Application filed December 19, 1921. Serial No. 523,469.

To all whom it may concern:

Be it known that I, EVERETT W. VARNEY, a citizen of the United States, residing at Newton, in the county of Middlesex and 5 State of Massachusetts, have invented certain Improvements in Methods of Making Shoes, of which the following description, in connection with the accompanying drawings, is a specification, like reference characters on the drawings indicating like parts in the several figures.

This invention relates to the manufacture of shoes, and particularly to methods of making shoes, for example welt shoes. 15 In lasting the sides of shoes in which the upper is to be finally secured to a lip or rib on the innersole, such as welt shoes, it is a usual practice to tension successive portions of the upper along the sides of the shoe and to secure each portion in lasted position by a stout, temporary lasting tack which is only partially driven to facilitate its subsequent removal. This side lasting operation usually follows that of pulling 20 over and precedes the end lasting operation. After the ends of the shoe have been lasted they are put through a separate operation of upper stapling. This operation consists of inserting small wire staples 25 through the upper and lip or rib of the innersole in a direction substantially parallel to the plane of the last bottom. The run of work in the factory is preferably so arranged that the shoes, after having 30 reached the state of manufacture above indicated, may remain on the racks for a considerable length of time, for example over night, to allow the uppers to become completely set to the contour of the last. After 35 the uppers have set the temporary lasting tacks are withdrawn and the staples, which remain permanently in the shoe, serve to retain the set upper in lasted position during subsequent operations such as upper trimming, if this has not previously been done, 40 and inseam sewing or welting.

Objects of this invention are to effect improved lasting of the upper and to reduce the number of times the shoes have to be

handled by eliminating upper stapling as 50 a separate operation.

The method consists in lasting the upper and, while the upper is held in lasted condition, securing the upper both by temporary fastenings which are to be withdrawn and by other fastenings which may be permanent and remain in the shoe. As herein illustrated by way of example, successive portions of the upper are worked into lasted position and each of these portions secured by a lasting tack and concurrently by a staple inserted through the upper and innersole rib. As herein set forth successive portions of the upper are tensioned and two temporary lasting tacks are driven 55 through the lasted portion, the tacks being preferably spaced apart a distance substantially equal to the extent of the portion tensioned, and a staple is inserted between the tacks. Preferably the lasted portion is 60 wiped into the angle between the feather of the innersole and the rib or shoulder of the innersole and the tack or tacks are driven through the upper in said angle 65 through the innersole and into the last while 70 the staple is driven parallel to the last bottom through the upper and lip or rib of the innersole. Thus each portion of the upper is not only tensioned and temporarily secured from drawing back, but also each 75 portion is worked into finally lasted position and permanently secured in that position concurrently with the temporary fastening operation.

Also, as herein shown, a staple and a tack 85 may be inserted in alignment transversely of the shoe edge, for example, by first inserting a staple and then inserting a tack outside of the staple or behind the staple, considering the operator's viewpoint. Thus 90 each portion of the upper is worked into finally lasted position and secured by a permanent fastening, and, concurrently, and while the upper is still held in lasted position, a tack is inserted closely adjacent to 95 and behind the staple, so that the fastenings are in alignment with the direction of strain upon the upper, the tack serving tem-

porarily to prevent reaction of the tensioned portion of the upper and to hold it in lasted position until it has set.

In the drawings,

5 Fig. 1 is a perspective view of a shoe lasted in accordance with the present invention;

10 Fig. 2 is a perspective view of operating instrumentalities by the use of which the invention may be practiced;

15 Figs. 3 and 4 are sectional details showing instrumentalities which may be used when the fastenings are inserted in transverse alinement; and

20 Fig. 5 is a fragmentary sectional view 15 showing a staple and tack in transverse alinement holding a portion of the upper in lasted position.

25 In carrying out the method of the present invention an innersole 2 and upper 4 are assembled on a last 6 and pulled over in the usual manner, the tacks driven by the pulling-over machine being indicated at 8. Successive portions of the upper along the sides 30 of the shoe are subjected to upward and inward tension and are wiped into the angle between the feather 10 and lip or rib 12 of the innersole 2. Then each lasted portion, 35 while still held in wiped-in position, is secured both by a temporary tack or tacks 14 driven through the upper and innersole into the last in the angle between the feather 10 and the rib 12 and concurrently by a permanent fastening such as a staple 16 driven 40 through the upper and rib 12 in a direction substantially parallel to the last bottom. After one or both sides of the upper have been thus lasted a tack or tacks 18 may be driven completely in at the breast end of the heel-seat at each side of the shoe.

45 The operations of end lasting and, if desired, upper trimming, may now be performed as usual, and after the shoes have remained on the racks a sufficient time to allow the uppers to set in lasted condition the temporary tacks 14 are withdrawn and the inseam sewing or welting operation may immediately follow.

50 It will be apparent that by this method the separate handling of the shoes incident to the use of an upper stapling machine or its equivalent is entirely dispensed with and that upper stapling as a separate operation is eliminated with a consequent very material saving in the time required for the manufacture of shoes.

55 For the purpose of illustrating one practical way of practicing the present invention, the drawings show a machine of the hand method type having in general the organization disclosed in United States Letters Patent No. 1,530,329, granted March 17, 1925, on application of Brock and Seely. 60 As disclosed in said application the machine

is organized to drive at each operation either two tacks completely or a staple, the change from tacks to staples being made by shifting a hand lever. For the purpose of practising the method of the present invention, however, the machine is organized so that the drivers will partially insert a tack or tacks concurrently with the insertion of a staple, the supply of tacks being, of course, arranged to continue while staples are being driven. For this purpose the driver stop is reduced in height so that instead of suspending the driving of tacks completely the tacks will be partially driven through the upper, innersole and into the last. Consequently the machine will operate in each cycle to insert two tacks partially into the work to hold the lasted upper under tension and, while the lasted portion is held wiped into the angle between the feather and rib of the innersole, will insert a staple through the upper and rib of the innersole and clench it to hold the upper permanently in finally lasted position, the staple being preferably located centrally between the two tacks. When the hand lever is operated to discontinue the driving of staples the driver stops will be withdrawn so that tacks may be completely driven, as is desirable when lasting the portion of the upper and counter adjacent to the breast line of the heel-seat, as indicated at 18 in Fig. 2.

55 In Fig. 2 a rest against which the work is upheld by the operator is designated by the numeral 22, the lateral position of the work being determined by an edge gage 24. A gripper 26 is operated in the usual manner in machines of this type to updraw and overdraw the upper, the gripper being given a plaiting motion when required to take care of the stock at the sharply curved portion of the periphery of the shoe between the shank and the ball. A combined tack block and staple nozzle is provided in a wiper 28 which is reciprocated in time relation to the operation of the gripper 26 to wipe the tensioned upper into the angle between the feather 10 and rib 12 of the innersole 2. The wiper preferably is provided with two tack pockets 29, 30 to which tacks are fed in any suitable manner when the wiper is in its retracted position, for example, in the manner disclosed in the prior application above referred to. After the gripper 26 has tensioned a portion of the upper 4, the wiper 28 advances to wipe in and hold the tensioned portion in lasted position and drivers 32 are caused to descend to drive the tacks in the tack pockets of the wiper partially into the shoe and last. While the wiper, as indicated in Fig. 2, is still holding the upper in lasted position in the angle between the rib and feather a staple is driven through an opening 34 in the wiper in a direction substantially parallel with the bottom of the 105

last and is clenched against an anvil 36 which moves in time relation to the wiper to back up the rib on its inner face while the staple is being inserted.

5 While the method as illustrated herein, in which two tacks are inserted for each staple, will be satisfactory for lasting certain kinds of work, it is apparent that in other kinds of work where more resistant uppers are 10 to be handled, it may be desirable, and is understood to be within the present invention, to insert a staple for each tack inserted; for example, the feeding of tacks to one of the tack pockets or the operation of 15 one of the drivers may be discontinued by expedients well known in the art, with the result that a single tack and a staple will be inserted in each lasted portion of the upper.

20 Furthermore, as disclosed in Figs. 3, 4 and 5, the tacking and stapling mechanisms may be arranged in alignment with respect to the direction of strain of the upper and to the direction of reciprocation of the wiper 28, that is, in transverse alignment with respect to the edge of the shoe. The tack block 28' is provided with a single tack pocket arranged over the channel 42 through which the staple 16 is driven by a driver 45.

25 The staple channel 42 is wider than the tack head and the legs of the staple are guided in grooves 43 in the walls of the channel at each side of the passage for the tack. Preferably a staple is driven prior to the tack, and concurrently, that is, immediately afterward in the same cycle and while the upper is held in finally lasted position, a tack is driven as shown in Fig. 5. The tensioned portion of the upper is thus permanently secured in finally lasted position by the 30 staple and the lasting strain in line with the staple is temporarily held by the tack until the upper has set. When the upper has set, the tack may be removed and the succeeding 35 shoemaking operations performed in the usual manner.

It is apparent that by the method of the present invention the plurality of concurrently inserted fastenings are inserted in 40 convergent or intersecting directions, and that when two kinds of such staples and tacks are thus inserted, one kind, the staple, will secure the upper permanently to the innersole, and the other kind, the tacks, will secure the upper temporarily to the last. Since the upper is thus secured to the last 45 the reaction of the tensioned upper is sustained by the last without danger of disturbing the lip as might happen if the upper were secured to the innersole only.

Having thus described my invention, what I claim as new and desire to secure by Letters Patent of the United States is:

1. That improvement in methods of making shoes which consists in working suc-

cessive portions of an upper over a last and fastening each portion of the upper concurrently by metallic fastenings of different kinds.

2. That improvement in methods of making shoes which consists in working successive portions of an upper over a last and securing each portion of the upper as it is overworked by separate metallic securing means of different kinds to the last and to the innersole respectively.

3. That improvement in methods of making shoes which consists in working successive portions of an upper over a last and securing each portion of the upper while it is held worked into lasted position by a fastening driven through the upper, innersole and into the last and substantially simultaneously with said fastening by a fastening driven through the upper and innersole rib, said fastenings being arranged in alternation along the periphery of the shoe.

4. That improvement in methods of making shoes which consists in working successive portions of an upper into lasted position and concurrently inserting a plurality of fastenings through each lasted portion in convergent directions.

5. That improvement in methods of making shoes which consists in working successive portions of an upper into lasted position and concurrently inserting through each portion a plurality of fastenings in different directions.

6. That improvement in methods of making shoes which consists in working successive portions of an upper into lasted position and while each portion is held in worked over position inserting through each portion fastenings of different kinds in intersecting directions.

7. That improvement in methods of making shoes which consists in working successive portions of an upper into lasted position and concurrently fastening each portion to the last by one kind of fastening inserted through the upper and sole and to the innersole by another kind of fastening inserted through the upper and the rib of the innersole.

8. That improvement in methods of making shoes which consists in working successive portions of an upper into lasted position and inserting fastenings to secure each portion temporarily to the last and permanently to the innersole.

9. That improvement in methods of making shoes which consists in working successive portions of an upper into lasted position and inserting concurrently fastenings to secure each portion temporarily to the last by one kind of fastening and permanently to the innersole by another kind of fastening.

10. That improvement in methods of making shoes which consists in working an upper

into lasted position over a last and inserting concurrently through the same lasted portion of the upper both temporary securing means and other securing means which, after the upper has set and the temporary securing means are withdrawn, will serve to hold the upper in lasted position during subsequent operations.

11. That improvement in methods of making shoes which consists in tensioning successive portions of a shoe upper, inserting through each tensioned portion a temporary tack and concurrently inserting through the upper and innersole rib a permanent fastening.

12. That improvement in methods of making shoes which consists in working an upper into lasted position over a last and inserting concurrently through the same lasted portion of the upper both temporary securing means and permanent securing means which, after the upper has set and the temporary securing means are withdrawn, will serve to hold the upper in finally lasted position during subsequent operations.

13. That improvement in methods of making shoes which consists in tensioning successive portions of a shoe upper, inserting through each tensioned portion a temporary tack and, concurrently while the portion of upper is held in finally lasted position, inserting through the upper and innersole rib a permanent staple.

14. That improvement in methods of making shoes which consists in tensioning successive portions of a welt shoe upper progressively along the periphery of a shoe, wiping the upper into the angle between the feather and rib of the inner sole, and inserting through the wiped portion while it is held in wiped position both a tack and a staple.

15. That improvement in methods of making shoes which consists in tensioning successive portions of a welt shoe upper progressively along the periphery of a shoe, wiping the upper into the angle between the feather and rib of the innersole, and inserting through the wiped portion, while it is held in wiped position, a lasting tack and a staple.

16. That improvement in methods of making shoes which consists in gripping locally successive portions of a shoe upper, tensioning each portion upwardly and over the bottom of the last, holding the portion in lasted position upon the shoe bottom, while the portion is so held securing it by a temporary fastening sufficient to hold the portion in lasted position when released and while the portion is still held inserting another fastening sufficient to hold the portion in lasted position after it has set in lasted condition and the temporary fastenings have been withdrawn, allowing the upper to set,

removing the temporary fastenings, and completing the shoe in the usual manner.

17. That improvement in methods of making shoes which consists in tensioning successive portions of a welt shoe upper progressively along the periphery of a shoe, wiping the upper into the angle between the feather and rib of the innersole, and inserting through the wiped portion while it is held in wiped position two fastenings in alinement with the direction in which the upper is wiped, one of said fastenings holding the upper to the last in strained condition and the other of said fastenings having a holding power sufficient to retain the upper in lasted position after it has set and the first fastening has been removed.

18. That improvement in methods of making shoes which consists in tensioning successive portions of a welt shoe upper progressively along the periphery of a shoe, wiping each portion of the upper into the angle between the feather and rib of the innersole, inserting through the wiped portion a tack, and while it is held in wiped position inserting a staple adjacent to the lasting tack.

19. That improvement in methods of making shoes which consists in tensioning successive portions of a welt shoe upper progressively along the periphery of a shoe, wiping the upper into the angle between the feather and rib of the innersole, inserting through the wiped portion while it is held in wiped position a temporary lasting tack, and inserting adjacent to the tack a further securing element having a holding power sufficient to retain the upper in lasted position after it has set and the tack has been removed.

20. That improvement in methods of making shoes which consists in tensioning successive portions of a welt shoe upper progressively along the periphery of a shoe, wiping each portion of the upper into the angle between the feather and rib of the innersole, and inserting through each wiped portion while it is held in wiped position both a tack and a staple in alinement with each other transversely of the shoe edge.

21. That improvement in methods of making shoes which consists in tensioning successive portions of a welt shoe upper progressively along the periphery of a shoe, wiping each portion of the upper into the angle between the feather and rib of the innersole, and inserting through each wiped portion while it is held in wiped position both a tack and a staple, said fastenings being arranged in alinement with respect to the direction of strain of the upper.

22. That improvement in methods of making welt shoes which consists in wiping the upper into the angle between the feather and rib of the innersole, inserting through the

same wiped portion while it is held in wiped position both temporary and permanent securing means, then allowing the upper to set, removing the temporary securing means, and proceeding with the manufacture of the shoe in the usual manner.

23. That improvement in methods of making shoes which consists in wiping the upper

upon the innersole, and inserting through the same portion of the upper while it is held in wiped position both a tack and a staple.

In testimony whereof I have signed my name to this specification.

EVERETT W. VARNEY.
